UNITED STATES PATENT OFFICE.

STEPHEN H. EMMENS, OF NEW YORK, N. Y.

APPARATUS FOR CONVEYING AND UTILIZING LIQUID AIR OR OXYGEN.

SPECIFICATION forming part of Letters Patent No. 651,029, dated June 5, 1900.

Application filed July 19, 1899. Serial No. 724,402. (No model.)

To all whom it may concern:

Be it known that I, STEPHEN HENRY EMMENS, a subject of the Queen of Great Britain and Ireland, and a resident of the borough of Richmond, in the city and State of New York, have invented a new and useful Improvement in Apparatus for Conveying and Utilizing Liquid Air or Oxygen, of which the following is a specification.

10 The primary object of this invention is to provide safe and effective means for economically conveying liquid air or liquid oxygen to oil-wells and for conveniently utilizing the same therein as a high explosive, and thus to avoid the risks attending the manufacture, 15 transport, and utilization of nitroglycerin. The improved package may obviously be employed to convey liquid air or oxygen for other uses.

20 The invention consists in a shipping and storing package of peculiar construction whereby liquid air or oxygen may be safely conveyed reasonable distances without any serious loss by evaporation and in certain 25 novel combinations of parts in a package of that description, as hereinafter set forth and claimed.

A sheet of drawings accompanies this specification as part thereof.

30 Figure 1 of the drawings represents an axial vertical section through said shipping and storing package; and Fig. 2, an axial section, on a larger scale, of its inner receptacle removed and provided with a detonating-cap 35 for use as a well-torpedo.

Like letters and numbers refer to like parts in both figures.

The body of the specific inner receptacle or torpedo A consists of a sheet-metal cylinder having a wide-open upper end 1 and a conoidal lower end 2, the latter terminating in a short cylindrical neck 3. Into this neck is inserted a brass tube 4, Fig. 2, open at both ends and filled with gunpowder tightly packed. The chamber 5 of the inner receptacle or torpedo is then loosely filled with greasy cotton-waste or other analogous combustible material introduced through the open end 1, and the remainder of the package being ready the charge of liquid air or oxygen is poured into said chamber 5. The remainder of the package consists of an open-

topped sheet-metal inner vessel B, inclosing the inner receptacle A, except its upper end, and forming around the same an annular chamber 6, which is filled or partly filled with the liquefied gas; a non-conducting body C, hereinafter more particularly described, of suitable felt or its equivalent, and a tightly-fitted lid D, of the same, forming a chamber 7, within which said inner receptacle A and inner vessel B are inclosed while stored or in transit; an outer open-topped sheet-metal case E, lined by said non-conducting body C, and an annular base F, that may be of wood, 65 attached externally to the bottom of said outer case E.

Passages 8 extend radially from the upper portion of the chamber 7 into a concentric annular cavity 9 within the body C, connected 70 in like manner with the lower portion of said chamber 7 by radial passages 10. The inner ends of the passages 10 communicate with a radial depression 11 in the bottom of said chamber 7, which is in turn connected by 75 radial passages 12 with a central hole 13, extending downward through the bottom of the case E. This central hole 13 communicates with the space 14 within the annular base F and through radial passages 15 in said base 80 with the outer atmosphere.

The liquid air or oxygen in the inner vessel B as it evaporates flows out through said passages 8 into the annular cavity 9 and thence escapes through the passages 10, depression 11, passages 12, bottom hole 13, space 14, and passages 15 into the outer atmosphere, thus conveying off whatever heat may find its way from the outside atmosphere through the case E, non-conducting cap D, 90 and body C, and consequently reducing the evaporation of the contents of the inner vessel to a minimum. The enveloping current of escaping vapor that fills the annular cavity 9 is protected against condensation by the 95 non-conducting walls of this cavity, its inner and outer walls both being of this description. The inner receptacle or torpedo A, standing within the inner vessel B, is thus kept at the temperature of the liquefied gas until it is required for use. The lid D is then removed, the torpedo withdrawn, a detonating-cap 16, Fig. 2, charged with a suitable fulminate, is applied to the protruding lower end of the

tube 4, and the torpedo is dropped endwise into the well without any serious loss of efficiency by the evaporation of its charge. When the cap 16 strikes the rock or water or oil at the bottom of the well, the torpedo is exploded by the detonation of the fulminate and gunpowder, causing the mixture of liquid air or oxygen and combustible to unite explosively.

10 The torpedo formed by the specific inner receptacle shown at A forms no part of the present invention nor said inner receptacle, except as an element in the general combination of parts hereinafter claimed.

15 More than one inner receptacle or torpedo may, if required, be inclosed within a single package, a perforated foot flange or rim on the case E may take the place of the base F, and other like modifications will suggest themselves to those skilled in the art.

Having thus described said improvement, I claim as my invention and desire to patent under this specification—

1. A package for conveying liquid air or oxygen consisting of an open-ended inner receptacle adapted for use as a torpedo for exploding oil-wells, an open-topped inner vessel forming an annular chamber around said inner receptacle, a chambered main body and 25 a lid for the same of non-conducting material inclosing said inner receptacle and inner vessel, an outer vessel or case of which said non-conducting body forms the lining, and a base attached externally to the bottom of said case; 30 said non-conducting body, case and base being provided with escape passages, and said inner receptacle and inner vessel being charged with the liquefied gas.

2. In a package for conveying liquid air or 40 oxygen, the combination with an open-topped inner vessel, charged with the liquefied gas, of a non-conducting body and lid forming a chamber within which said inner vessel is in-

closed, and constructed with an annular cavity the inner and outer walls of which are non-conducting in communication with both the upper and lower parts of said chamber, an outer case having an opening in its bottom in communication with said chamber, and a base provided with radial passages in communication with said bottom hole and with the outer atmosphere.

3. In a package for conveying liquid air or oxygen, the combination with an inner receptacle charged with the liquefied gas of a non-conducting body and lid forming a chamber that incloses said inner receptacle, said body being further constructed with an annular cavity that surrounds said chamber and the inner and outer walls of which are non-conductors in communication with the upper part of said chamber and indirectly in communication at bottom with the outer atmosphere, and an outer case of which said non-conducting body forms the lining.

4. In a package for conveying liquid air or oxygen, the combination with an inner receptacle charged with the liquefied gas of a non-conducting body and lid forming a chamber inclosing said inner receptacle and constructed with an annular cavity surrounding said chamber and separated from said chamber by a heat-insulating wall, said cavity being in communication with said chamber at top and indirectly in communication with the outer atmosphere at bottom, whereby evaporation within said chamber is retarded by an enveloping current of escaping vapor within said annular cavity, and the condensation of the escaping vapor within said cavity is prevented, substantially as hereinbefore specified.
